CLAIM

The ornamental design for a flower pot, as shown and described.

DESCRIPTION

FIG. 1 is a perspective view of a flower pot showing our new design;

FIG. 2 is an enlarged perspective view of the detail 2 shown in FIG. 1 thereof;

FIG. 3 is a front elevational view thereof;

FIG. 4 is a right side elevational view thereof, the left side being a mirror image thereof; and,

FIG. 5 is a bottom plan view thereof.
